US00D995125S

(12) **United States Design Patent** (10) Patent No.: **US D995,125 S**
 Botero Ospina et al. (45) Date of Patent: **** Aug. 15, 2023**

(54) **TISSUE**

- (71) Applicant: **Kimberly-Clark Worldwide, Inc.**, Neenah, WI (US)
- (72) Inventors: **Gabriel F. Botero Ospina**, London (GB); **Massimo Cagnone**, Prato Sesia (IT)
- (73) Assignee: **Kimberly-Clark Worldwide, Inc.**, Neenah, WI (US)
- (**) Term: **15 Years**

(21) Appl. No.: **29/761,793**(22) Filed: **Dec. 11, 2020**(51) **LOC (14) Cl.** **05-06**
 (52) **U.S. Cl.** USPC ..... **D5/55; D5/57**(58) **Field of Classification Search**
